UNITED STATES PATENT OFFICE.

THEODORE WILLARD CASE, OF AUBURN, NEW YORK, ASSIGNOR TO CASE RESEARCH LABORATORY INCORPORATED, OF AUBURN, NEW YORK, A CORPORATION OF NEW YORK.

ELECTRICAL APPARATUS.

Application filed January 25, 1923. Serial No. 614,762.

This invention relates to a new and improved electrical apparatus particularly adapted for translating sound waves into light waves, or variations of light waves which can be efficiently photographed or reproduced upon a film, thereby constituting a translatable film record of sound waves, particularly articulate or musical sound waves.

10 I have produced, and my invention includes as a separable element, an instantaneous varying actinic light source of a most efficient character, particularly applicable to the production of a clear, distinct and readily translatable photograph of electrical variations, especially as effected by variations in sound waves. The main object of the invention is the production of an improved apparatus of great sensitivity to sound variations, and from which a new, novel and translatable film record can be made, and the invention includes as the essential element a stable source of concentrated light approaching as close as is practical to a point of light which can be varied in accordance with sound waves, and is highly effective for photographing through the comparatively minute area of a camera slit or opening, past which the photographic film moves.

15 The very essentials of my invention are two electrodes arranged in very close proximity and surrounded by an easily ionizable gas, such as preferably helium, which gives 20 a highly actinic light for photographic purposes, altho argon may be satisfactorily used.

25 My invention has the further advantage that it permits the insulation of the negative electrode, or the covering of portions of the negative electrode with insulating material so as to confine the negative glow to the area desired which when a lens is to be used should be very small rather than diffused over a large area.

The tube or sound reactive lamp of my invention does not require the use of a high voltage high frequency current, but is operated as hereinafter described by direct current of comparatively low voltage. The operation can be carried on satisfactorily with a voltage on the lamp of from 200 to 400 volts, the required voltage varying somewhat in accordance with the pressure 30 of the gas within the tube.

Other objects and advantages relate to the details of form, and construction of the apparatus, all as will more fully appear from the following description, taken in connection with the accompanying drawings, in which:

Figure 1 is a diagrammatic illustration of an embodiment of my invention.

Figure 2 is a diagrammatic illustration of a further embodiment of my invention.

Figure 3 is a diagrammatic illustration of a further embodiment of my invention.

As illustrated in Figure 1, the apparatus may comprise a microphone —1— connected in circuit with a source of potential 70 as the battery —2— and with the primary —3— of a transformer —4—, the secondary —5— of which is connected in circuit with the filament —6— and the grid —7— of an electron-discharge device —8—, the plate 75 —9— of which is connected in circuit with the filament —6—, such circuit including a source of potential, as the battery —10— and a primary —11— of a transformer —12—, the secondary —13— of which is 80 connected in circuit with the spaced electrodes —14— and —15— of the sound wave reactive lamp —16— such circuit preferably including a source of potential —17— for maintaining a continuous discharge between 85 the electrodes —14— and —15—. The bulb of the lamp —16— is filled with an easily ionizable gas, preferably helium, which gives a highly actinic light for photographic purposes and the electrodes —14— 90 and —15— are arranged in close proximity to each other, whereby a highly concentrated and comparatively small light is produced peculiarly adapted for photographic purposes in connection with the usual camera 95 which embodies a very narrow slit or opening —23— for the passage of the light to the moving film —18—.

Further concentration may be effected by the interposition of a concentrating lens 100 —19— as illustrated. The very essential of the invention is the close proximity of the electrodes to each other combined with the easily ionizable gas within the tube —16— and surrounding the electrodes. The electrodes —14— and —15— may be of various forms and as illustrated in Figure 1, are two small plates, while in Figure 2 the electrode —21— is in the form of a cylinder of comparatively small diameter, and the elec- 110

trode —22— may be a wire which terminates preferably adjacent the lower end of the cylinder and is positioned substantially axially of the cylinder, and in this construction of apparatus, the cylindrical electrode —21— is negative and the electrode —22— is positive, whereby the negative glow is concentrated within the cylindrical electrode in a manner quite advantageous for photographic purposes.

When referring in the specification and claims of this application to the electrodes being arranged in close proximity, I mean that the electrodes are spaced apart a distance not greater than one-quarter of an inch, and preferably not greater than one-eighth of an inch, and for the purpose of accomplishing the construction illustrated in Figure 2, the cylindrical electrode —21— may perhaps preferably be approximately three-eighths of an inch in diameter.

As above stated, the light produced at the lamp —16— is comparatively small and highly concentrated, and is produced by a direct current of comparatively low voltage and is highly sensitive to variations in electric current as effected by variations in sound waves acting upon the microphone —1—.

30 The filament —6— may be heated in any suitable manner as by a heating circuit including a source of potential —24—. In Figure 3 a further form of my invention is illustrated, and in the hook-up shown, the transformer —12— is omitted and the lamp —25— is inserted in the circuit between the filament —6— and the plate —9— in place of the primary —11— of the said transformer.

40 It is found that this hook-up operates in an efficient manner when a current of about 350 volts is applied to the circuit and the battery —10— should be adapted for that purpose. The lamp —25— is of slightly different construction than that shown in Figure 2, the electrode —26— being in the form of a comparatively small wire ring, and the electrode —27— may be constituted of the end of the conductor or wire which penetrates the base of the lamp bulb and this wire or electrode projects but a short distance within the lamp, and is, therefore, relatively small for the purpose of producing a concentrated light of comparatively small area. For illustration, the electrode —27— may project one-eighth of an inch within the lamp and should be of as small diameter as is practical, and is preferably spaced $\frac{1}{8}$ th to $\frac{1}{16}$ th of an inch from the ring —26—. Obviously, however, I do not desire to limit myself to the exact length of projection of the electrode or its exact diameter with the understanding that I am describing a preferred form. The electrode —27— is the negative electrode in the struc-

ture of Figure 3 for the reason that in this apparatus a concentrated negative glow is used.

I have further discovered that if the electrode which is to be used as the negative electrode be coated with an alkaline earth oxide such as calcium, barium or strontium, or have the oxides or oxide, or the volatilization product of such oxides, deposited thereon or if the electrode be formed of or include a radio-active material, the voltage at which the lamp may be operated is very materially reduced, and once started the bulb will carry a much greater current, and the subject matter of that discovery is being made the basis of a separate application.

Altho the structure of Figure 3 operates in a satisfactory manner, yet the interposition of the transformer —12— as illustrated in Figures 1 and 2 has in my present opinion, certain advantages, particularly when the secondary —13— is of low resistance (as for instance 120 ohms) when compared with the primary —11—.

In the apparatus illustrated in the drawings, there is shown a single step of amplification which embodies an electron discharge tube —8— and suitable circuit connections. It will be obvious that other steps of amplification may be inserted in the apparatus should that be desirable, and that where the same is not required or desirable, the electron discharge tube —8— and its circuits may be omitted and the secondary —13— of the transformer —12— be utilized as the secondary of the transformer —4— in place of the secondary —5— illustrated in the drawings.

By the use of the expression "an easily ionizable gas," as used in the specification and claims hereof, I do not mean to limit myself to one particular kind of gas, but rather use the expression as illustrative of any easily ionizable gas, whether it be gas of a single kind, or a combination or mixture of gases, as for instance, helium and argon.

Altho I have shown and described specific constructions of apparatus as illustrative of embodiments of my invention, I do not desire to limit myself to the details of form, construction or arrangement, or to the use of any particular gas within the lamp —16— so long as it be an easily ionizable gas, except where the said particular elements and details are specifically set forth in the claims hereto appended.

I claim:

1. In an apparatus for producing a photographic record of light wave variations corresponding to electrical variations, a bulb containing a pair of electrodes spaced apart a distance not substantially greater than one-eighth of an inch, and a gas within the bulb at such a pressure that a concentrated

- glow is produced about the negative electrode separate from the anode glow at an operating voltage not substantially greater than 400 volts direct current.
2. In an apparatus for producing a photographic record of light wave variations corresponding to electrical variations, a bulb containing a pair of electrodes spaced apart a distance not substantially greater than one-eighth of an inch, and helium within the bulb at such a pressure that a concentrated glow is produced about the negative electrode separate from the anode glow at an operating voltage not substantially greater than 400 volts direct current.
3. In an apparatus for producing a photographic record of light wave variations corresponding to electrical variations, a bulb containing a pair of spaced electrodes, and a gas within the bulb at such a pressure that 20 a concentrated glow is produced about the negative electrode separate from the anode glow at an operating voltage not substantially greater than 400 volts direct current.
4. In an apparatus for producing a photographic record of light wave variations corresponding to electrical variations, a bulb containing a pair of spaced electrodes, and helium within the bulb at such a pressure that a concentrated glow is produced about 30 the negative electrode separate from the anode glow at an operating voltage not substantially greater than 400 volts direct current.

In witness whereof I have hereunto set my 35
hand this 17th day of January, 1923.

THEODORE WILLARD CASE.
